UNITED STATES PATENT OFFICE.

HARRY S. COWLES, OF CHICAGO, ILLINOIS, ASSIGNOR OF ONE-HALF TO ROLLA R. COWLES, OF CHICAGO, ILLINOIS.

GAME APPARATUS.

1,164,993.

Specification of Letters Patent. Patented Dec. 21, 1915.

Application filed October 5, 1914. Serial No. 864,993.

To all whom it may concern:

Be it known that I, HARRY S. COWLES, a citizen of the United States, and a resident of Chicago, county of Cook, and State of Illinois, have invented certain new and useful Improvements in Game Apparatus, of which the following is declared to be a full, clear, and exact description.

This invention relates to games, and, more particularly, to apparatus for playing games where various kinds of "plays" occur in the game and where score is to be kept of the several different kinds of "plays." The device has been designed with special reference to playing a game simulating the game of baseball, although it may be used for playing many other similarly well known games. The object is to provide a simple and amusing device upon which a spherical body, such as a small ball or marble, may be rolled, and having a runway formed with a large number of depressions, in any of which the spherical body may lodge when its momentum is spent, the names of the different plays in the game of baseball, or any other game, being printed adjacent to said depressions, whereby the player may observe the value of his play.

To such ends, this invention consists in the several novel features of arrangement, construction and combination of parts, herein-after fully described and claimed.

The invention is clearly illustrated in the drawing herewith, in which:

Figure 1 is a perspective view of a game device embodying a simple form of the present invention; Fig. 2 is a view of a spherical body used in connection with the device shown in Fig. 1, for playing the game; Fig. 3 is a detail, longitudinal section through the device seen in Fig. 1, partly broken away; Fig. 4 is a face view of a score sheet which may accompany the device; and Fig. 5 is a longitudinal section through one end of a slightly modified form of the invention.

Referring to the said drawing, 10, designates a strip of material, such as wood or metal, having in its upper face a length-wise running groove, 11, forming a runway for a spherical body, such as a small ball, marble or the like, 12. Preferably, said groove is centrally disposed between the sides of the strip 10, and the upper faces, 13, of the adjacent portions slope down-

ward toward said groove to prevent the ball or marble from rolling off the strip in case it escapes from the groove, 11, when being propelled rapidly therethrough. The downwardly sloping faces adjacent the central groove act to permit the ball or marble to return to the groove, and one of said faces forms a convenient place upon which to print the various plays to be made in playing the game. In the bottom of said groove are a number of depressions, 14, arranged in alinement with each other and extending practically along the entire length of the groove, and said depressions are here shown in the form of transversely extending corrugations, which, for the sake of convenience, may be formed by a strip of corrugated metal, 15, placed on the bottom of the groove and secured therein. Preferably, the corrugated strip is permanently secured in the groove, and I have shown its ends bent down over the ends of the strip, 10, as at 16, 17, and tacked thereto by tacks, nails, or any other like fastening device, 18. If desired, the strip may be tacked to the bottom of the groove at a number of places along its length. To prevent the ball or marble from running off the far end of the runway, I provide a stop at that end, and it is here shown as formed by bending up the corrugated strip, 15, as at 19, before forming the downward bend, 17. Obviously, any equivalent expedient may be employed for forming a stop at the far end of the runway. At the initial or near end of the runway, is a smooth or hollowed-out place upon which the ball or marble is placed when it is to be propelled down the runway, and I have shown the strip, 15, as formed with a downwardly curved portion, 20, for this purpose.

On one of the inclined or sloping faces, 13, of the strip, 10, or on a strip of paper, cardboard, or the like, 21, secured to said strip, 10, are printed words and symbols designating the various "plays" occurring in the game which is to be played, here shown as comprising the various plays occurring in the game of baseball, there being one "play" designated opposite each groove of the corrugated bottom of the runway. Any one skilled in this art, will readily recognize the kinds of plays designated by the words or symbols printed opposite the corrugations. Certain plays occur more fre-

quently than others in the game of baseball, and, consequently, those plays are represented more often. The device, therefore, is made more attractive and interesting, and a game can be played with this device wherein the score will partake of the nature of the scores or plays occurring in the actual game of baseball.

With the device thus far described is associated a card or sheet, 22, having printed thereon an ordinary "diamond" and other associated matter of a score board showing "outs," "balls," "strikes," etc., which are well-known to those skilled in this art. This card is used in keeping score when the game is played.

In use a marble or other small spherical body of less diameter than the width of the groove, 11, is laid upon the smooth, hollow place at the initial end of the strip, and the first player propels the marble along the runway by striking it with his finger. He then observes the value of the play opposite the corrugation where the marble stops, and keeps a record thereof, using the score board for this purpose. Small disks, buttons, or like objects, may be used for keeping score, and, after noting the value of his play, the player places a disk upon the score board over the spot designating the value of his play. For instance, if the marble should stop at the place indicated by "ball," he places a disk upon one of the first circles underneath the word "ball." If the next play is "out," he removes the disk from the circle and places it on the first circle under the word "out." If the play is "one base," he places a disk on the first "base" of the "diamond," clears the score card of all the disks except those on the circles marked "out," and advances this disk around the bases, as the following plays indicate.

It is to be noted that this game does not depend entirely upon chance for success in winning the game, but the player may use skill in propelling the ball along the runway and may become so efficient that he can control the ball to stop almost at any place he desires. As in the game of baseball, there

are two sides, and two or more persons may play the game, one half the number taking one side and the other half taking the other side, and they may play alternately through the usual nine "innings," unless there is a tie at the end of the ninth "inning," whereupon they may play until one side or the other wins the game.

In the modified form illustrated in Fig. 5, I have shown a plunger, 23, in a housing, 24, and having a stem 25, extending out through the end of the housing, which may be grasped by the player and drawn backward, against the action of a coil compressing spring, 26, confined between said plunger and the end of the housing, and which serves to return the plunger rapidly, and this contrivance may be used in propelling the marble or ball in place of striking it with the finger. This modified form shows the strip, 10^a, made of a piece of sheet metal having the corrugation, 14^a, formed directly therein.

More or less variation of the exact details of construction herein shown and described, is possible without departing from the spirit of this invention, and I desire, therefore, not to limit myself to the exact form shown and described but intend in the following claim to point out all of the invention disclosed herein.

I claim as new and desire to secure by Letters Patent:

A game apparatus comprising an elongated body having a centrally disposed lengthwise running groove formed in its upper surface, 85 said groove having ball seats in its bottom; a stop at one end of said groove, said body being provided with two wide downwardly inclined faces on its upper side which act as guideways to return a ball to said groove, and also to prevent the ball from rolling off the body, and game designations arranged on one of said faces in alignment with the ball seats in the said groove.
